(57) CLAIM

The ornamental design for a beverage container holder, as shown and described.

DESCRIPTION

FIG. 1 is a perspective view of a beverage container holder showing our new design.

FIG. 2 is a front view thereof.

FIG. 3 is a rear view thereof.

FIG. 4 is a right side view thereof.

FIG. 5 is a left side view thereof.

FIG. 6 is a top plan view thereof; and,

FIG. 7 is a bottom plan view thereof.

The broken lines are for illustrative purposes only and form no part of the claimed design.
